UNITED STATES PATENT OFFICE.

FREEMAN C. MERRILL, OF PARIS, MAINE.

PLOW.

SPECIFICATION forming part of Letters Patent No. 611,456, dated September 27, 1898.

Application filed August 27, 1897. Serial No. 649,677. (No model.)

To all whom it may concern:

Be it known that I, FREEMAN C. MERRILL, a citizen of the United States, residing at Paris, in the county of Oxford and State of Maine, have invented certain new and useful Improvements in Plows; and I do hereby declare that the following is a full, clear, and exact description of the invention, which will enable others skilled in the art to which it applies to make and use the same.

My invention relates to swivel or reversible plows; and it consists in a novel device for locking or fastening the moldboard to the standard when thrown from side to side.

It consists in an arm with a barbed or harpoon point in conjunction with means on the moldboard for receiving said point and means for rotating the arm in connection with means whereby the arm is held in contact with the moldboard by force of gravity.

The mechanism in which I have embodied my invention is shown in the drawings, in which—

Figure 1 is a side elevation of a plow with my improvement attached. Fig. 2 is an end view of the same. Fig. 3 is an end view of the plow with the moldboard locked on the side opposite to that it occupies in Fig. 2. Fig. 4 is a detail in perspective of the locking device.

The frame is of the ordinary construction, *a* being the beam, *b* the handles, and *p* the standard. *c*, the swivel or reversible moldboard, may be of the usual construction.

Upon the inner surface of it, however, near the upper and lower edges, respectively, I place the loops *d d* (see Figs. 2 and 3) to receive the locking or fastening device. An inclined plate *e* is secured to the upper surface

40 of the handles *b b*. This plate is shown in Fig. 4 in perspective. At the lower corners it is provided with studs *ff*. Centrally it has an aperture or opening *g*. In this opening is placed the rod *h*, which has somewhat above

45 the middle of its length an offset or angle *i* of sufficient length to engage each of the studs *ff*. Below the plate *e* is a plate *k*, secured to the frame. In the plate *k* is an opening *l*, which is vertically below the opening *g*.

50 Into this opening *l* is inserted the lower part of the rod *h*. Connected with the rod *h* above the plate *k* is the arm *m*. Its shape is shown

in Fig. 4. I prefer to connect it to the rod *h* by means of an opening in the arm *m* surrounding the rod *h*, to which the arm is fixed 55 by means of the screw *n*, which may be a bolt passing through holes in the arm and rod or a set-screw. When fixed in position by the screw *n*, the arm *m* should be in the same plane as the offset *i*. The point at which the 60 arm *m* is fixed to the rod *g* should be such that in no position which may be assumed by the rod will the arm *m* come into contact with or rest upon the plate *k*. The point of the arm is, as already shown, harpoon-shaped— 65 that is, barbed upon the sides—and it is also beveled upon the top from the point backward nearly to the barbs.

The operation of the device described is as follows: The swivel-moldboard being in position on one side the standard *p*, assume it is desired, at the end of a furrow, for instance, to reverse it, the rod *h* is turned toward the handles of the plow (thus disconnecting the arm *m* from the loop) until the offset rests 75 against the stud *f*, which is on the side opposite that on which is the moldboard. The plow is then thrown over, bringing the moldboard into position on the opposite side. Just before its forward end comes in contact 80 with the standard *p* the forward barb of the arm *m* engages with the upper loop *d* and is held constantly up to the loop by its weight, which is supported by the offset of the rod resting on the inclined plane of the plate *e*. The 85 moldboard is thus held in place by the arm *m* until again unlocked by turning the rod *h*, as before described. When the arm *m* is engaged with the loop *d*, thus locking the moldboard, the offset of the rod *h* is not in 90 contact with the stud *f*, but rests against the incline a slight distance in rear of the stud, allowing the full weight of the arm *m* to rest against the loop and keeping it firmly in place while the plow is in use. It is apparent that the office of the studs *ff* is to hold the arm *m* in proper position to engage the loops. 95

It should be stated that the point of the arm *m* should have a curved seat on either side in the rear of the barb, as shown in the drawings, the better to receive the projections on the moldboard.

As indicated, I do not confine myself to the

construction shown. The device may be varied in details, as is readily seen. For instance, the loops on the board may be replaced by other devices, as also the offset or angle i , or the inclined plane may be otherwise applied.

What I claim is—

1. In combination with a swivel-plow, loops upon the upper and lower edges of the mold-board, an arm suited to engage and hold either of said loops, a rod fixed to said arm, an offset upon said rod and an inclined plane having studs at the lower corners thereof, substantially as described.
2. In combination with a swivel-plow an arm with barbed end fixed to a rod having an offset resting upon an inclined plane, substantially as described.
3. The combination of the moldboard, the

loops upon the upper and lower edges thereof, 20 the barbed arm and rod with offsets, and the inclined plane with stops at its base, substantially as described.

4. In combination with a swivel-plow an arm with barbed end fixed to a rod having 25 an offset resting upon an inclined plane whereby the weight of said arm upon said inclined plane causes the barbed end of said arm to engage with the loop on the mold-board, thus holding it firmly in place, sub- 30 stantially as described.

In testimony that I claim the foregoing as my invention I have hereunto set my hand this 21st day of August, A. D. 1897.

FREEMAN C. MERRILL.
